(57) **CLAIM**

The ornamental design for an ink bottle, as shown and described.

DESCRIPTION

FIG. 1 is a top, right side, perspective view of an ornamental design for an ink bottle according to the present invention; FIG. 2 is a front elevational view thereof; FIG. 3 is a left side elevational view thereof; FIG. 4 is a right side elevational view thereof; FIG. 5 is a rear elevational view thereof; FIG. 6 is a top plan view thereof; and FIG. 7 is a bottom plan view thereof.

FIG. 8 is a top, right side, perspective view of an ornamental design for a second embodiment of an ink bottle according to the present invention;

FIG. 9 is a front elevational view of the ink bottle of FIG. 8;

FIG. 10 is a left side elevational view of the ink bottle of FIG. 8;

FIG. 11 is a right side elevational view of the ink bottle of FIG. 8;

FIG. 12 is a rear elevational view of the ink bottle of FIG. 8;

FIG. 13 is a top plan view of the ink bottle of FIG. 8; and, FIG. 14 is a bottom plan view of the ink bottle of FIG. 8. All portions shown in broken lines are for illustrative purposes only and form no part of the claimed design.
